UNITED STATES PATENT OFFICE.

EDWIN NORTON, OF CHICAGO, ILLINOIS, ASSIGNOR TO HIMSELF AND OLIVER W. NORTON, OF SAME PLACE.

PAINT-CAN.

SPECIFICATION forming part of Letters Patent No. 298,018, dated May 6, 1884.

Application filed February 11, 1884. (No model.)

To all whom it may concern:

Be it known that I, EDWIN NORTON, a citizen of the United States, residing in Chicago, in the county of Cook and State of Illinois, 5 have invented a new and useful Improvement in Paint-Cans; of which the following is a specification.

This invention relates to paint and other cans the heads or covers of which are double-seamed on after the can is filled. In double-seaming heads on filled cans no internal mandrel or support can of course be used, and therefore the flanges of the head and body forming the seam have heretofore always been folded or turned outwardly, so that the seam, when completed, lies on the outside wall of the can-body, and if a secondary slip-cover is to be applied an offset in the can-body or other provision must be made, so that the slip-cover can 15 fit over the seam, and still have a frictional bearing against the exterior surface of the can-body.

It is the object of the present invention to provide a can the head of which may be double-seamed on after the can is filled by folding the flanges of the head and body inwardly, so that the seam, when formed, will lie on top of the can and within the circumferential line of the can-body, and thus not interfere with the 25 application of a slip-cover to the can. This result I accomplish by, and herein my invention consists, providing the can with an interior shoulder, against which the flanges of the seam may be folded, and which thus serves, 30 so to speak, as an interior mandrel or support in forming the seam. This interior shoulder I form by turning a flange in at the top of the can-body and folding over it a seamless ring, so that the shoulder is composed of three thicknesses of tin and the solder uniting the same. The seamless ring has an upturned flange, 35 which is folded with the flange of the can-head into the double seam. As in this invention the seam rests snugly on the shoulder, the 40 seam and shoulder together give the can or its cover great strength and rigidity.

In the accompanying drawings, which form a part of this specification, and in which similar letters of reference indicate like parts, Figure 1 is a central vertical section of a can embodying my invention, and Figs. 2, 3, and 4

are sectional views showing the seam partially formed.

It should be remarked that in the drawings the thickness of the stock and size of the flanges 55 are greatly exaggerated, in order to show the same more clearly.

In the drawings, A represents the can-body, provided with the inturned flange *a* at its top, and B is the seamless ring, the lower part, *b*, 60 of which is folded over said flange *a* and soldered thereto, so as to form an interior shoulder or support on the can-body for the seam.

C is the can-head, provided with the upturned flange *c*, which is folded with the upright flange or part *b'* of the seamless ring into the double seam. The double seam, thus being folded inwardly, as shown, lies on top of the shoulder and within the circumferential line of the can-body, so that the slip-cover D 70 may be readily applied.

In Fig. 2 the seamless ring is shown folded over the flange of the can-body. In Fig. 3 the same is shown with the head applied, and in Fig. 4 the seamless ring is shown folded inwardly over the flange of the head, the next step being to turn the whole flat down upon the head, as shown in Fig. 1.

The interior shoulder should project in slightly farther than the inner edge of the double seam, so that the revolving disk or chuck 80 of the seaming-machine may derive some support from said shoulder, and still not interfere with the folding of the seam.

What I claim is—

1. The combination, with a can-body provided with an interior shoulder to support the seam while it is being formed, of a can-head secured thereto by a double seam folded inwardly and resting upon said shoulder, substantially as specified.

2. The combination of can-body A, provided with inturned flange *a*, with seamless ring B, folded over said flange, and can-head C, having upturned flange *c*, folded with said seamless ring inwardly into a double seam, substantially as specified.

EDWIN NORTON.
